SECTIONALIZED COMBINATION FLOAT AND PROTECTIVE INSULATING COVERING FOR PIPELINES

William W. Wilson, Raceland, La., assignor to Pipeline
Products and Services, Inc., Raceland, La.

Filed Jan. 23, 1974, Ser. No. 435,755

Term of patent 14 years

Int. Cl. D23—01

U.S. Cl. D23—1

FIG. 1

FIG. 2

FIG. 3

FIG. 9

FIG. 4

*Fig. 5**Fig. 6**Fig. 7**Fig. 8*FIG. 1 is a perspective view taken from one end of a sectionalized combination float and protective insulating cover for pipelines showing my new design;

FIG. 2 is another perspective view taken from the end opposite that shown in FIG. 1;

FIG. 3 is an elevational view of the end shown in FIG. 1;

FIG. 4 is an elevational view of the end shown in FIG. 2;

FIG. 5 is a top plan view thereof;

FIG. 6 is a bottom plan view thereof;

FIG. 7 is an elevational view taken from one side thereof;

FIG. 8 is an elevational view taken from the side opposite that shown in FIG. 7; and

FIG. 9 is a perspective view of one section thereof.

The broken line representation of retaining straps in FIGS. 1, 2 and 5 through 9 and the broken line repre-

sentation of a pipeline segment in FIGS. 1, 2 and 9 are for purposes of illustration only.

I claim:

The ornamental design for a sectionalized combination float and protective insulating covering for pipelines, as shown and described.
